UNITED STATES PATENT OFFICE.

JOSEPH McCRAKEN, OF BROOKLYN, NEW YORK.

SIZING HAT-BODIES.

Specification of Letters Patent No. 15,929, dated October 21, 1856.

To all whom it may concern:

Be it known that I, JOSEPH McCRAKEN, of Brooklyn, Kings county, State of New York, have invented certain new and useful 5 Improvements in Working or Sizing Hat-Bodies; and I do hereby declare the following to be a full description of the same.

The nature of my invention consists in working or sizing the hat body upon an elastic hollow cylindrical roller of india rubber or other elastic substance upon which the roll of felt or hat body is worked or sized while passing through the machine.

As a convenient and cheap material I 15 prefer making the cylindrical rollers out of india rubber hose pipe of any suitable size, and for the purpose of facilitating the discharge of the water from the inner folds of the felt I propose to have the sides of the 20 cylindrical roller perforated with a series of holes, so that the water may work through them into the hollow of the roller, and thereby let the water discharge, so as to dry out the roll of felt more rapidly to full or size 25 it up. But to describe my invention more particularly I will refer to the accompanying drawings forming a part of this specification, the same letters of reference wherever they occur referring to like parts.

30 Figure 1, is a perspective view of a perforated elastic cylindrical roller. Fig. 2, is a representation of a felt hat body. Fig. 3, is a representation of the cylindrical roller, having a roll of felt upon it.

35 Letter A, is a hollow cylindrical roller, made of vulcanized india rubber hose pipe. Through its sides are a series of perforations B. The object of these perforations is to allow the water of the interior folds of 40 the felt to escape rapidly; and of the elastic hollow roller, to sustain a perfect roll in the felt, and yet elastic enough to give the

roll of felt in passing through the machine an easy working motion so as to size up the most delicate felt textures.

45 Letter C, represents a hat body rolled upon the elastic cylindrical roller, and D, an outstretched hat body as seen before being rolled up.

In sizing hat bodies several are rolled 50 upon the roller at one time, and according to the work to be given to it, are changed to rollers of various sizes, that is, for the first working of the hat body small cylindrical rollers are used, but toward the last part of 55 the sizing operation when it is desirable to "harden" up the felt, a large roller is used; the object however in all cases being the same, that is, affording an elastic pressure to sustain the roll of felt under the outside 60 rolling and pressing operation while passing through the machine.

65 It will be obvious that various modifications may be made of my invention. I therefore do not wish to confine myself to the precise manner of making the india rubber elastic cylindrical roller, but desire the privilege of substituting any equivalent device for accomplishing the object hereinbefore set forth.

70 Having now described my invention and its operation I will proceed to set forth what I claim and desire to secure by Letters Patent of the United States.

75 What I claim and desire to secure is—
The use of the india rubber or other elastic perforated cylindrical roller, for working or sizing hat bodies upon when constructed in the manner, and operated in the mode substantially hereinbefore set forth.

80 JOSEPH McCRAKEN.
